(57) **CLAIM**

The ornamental design for a simulative flame head for an electronic candle as shown and described.

DESCRIPTION

FIG. 1 is a front elevational view of a simulative flame head for an electronic candle showing my new design;

FIG. 2 is a left side view thereof;

FIG. 3 is a perspective view thereof, and,

FIG. 4 is a second perspective view thereof in a use condition.

The rear elevational view is the same as the front elevational view.

The right side view is the same as the left side view.

The broken lines in FIG. 4 illustrate environmental features that form no part of the claimed design.

1 Claim, 4 Drawing Sheets

FIG.1

FIG.2

FIG.3
